(57) **CLAIM**

The ornamental design for an arm strap for mobile computer, as shown and described.

DESCRIPTION

FIG. 1 is a top front right perspective view of an arm strap for mobile computer showing my new design;

FIG. 2 is a top front left perspective view thereof;

FIG. 3 is a top rear right perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is a top rear right perspective view thereof in the stitched state.

The broken lines represent portions of the article which form no part of the claimed design.
